UNITED STATES PATENT OFFICE.

WILLIAM C. BLASKE, OF CHICAGO, ILLINOIS, ASSIGNOR, BY MESNE ASSIGNMENTS, TO
HEAT SAVER COMPANY, OF CHICAGO, ILLINOIS, A CORPORATION.

FUEL-SAVING DEVICE.

1,114,959.

Specification of Letters Patent. Patented Oct. 27, 1914.

Application filed November 22, 1913. Serial No. 802,387.

To all whom it may concern:

Be it known that I, WILLIAM C. BLASKE, a citizen of the United States, residing at Chicago, in the county of Cook and State of Illinois, have invented new and useful Improvements in Fuel-Saving Devices, of which the following is a specification.

The present invention relates to new and useful improvements in fuel saving apparatus as described in my co-pending application, Serial No. 799,044, filed November 3, 1913.

The invention has for an object to provide means for supporting and retaining the air pre-heating chamber within the smoke flue which will greatly reduce the cost of manufacture of such devices and at the same time present a strong and efficient structure which will render the device commercially desirable.

A further object of the invention is to provide an air pre-heating chamber for devices of this character having a large heating surface wherein the cold air coming into the chamber will be thoroughly pre-heated before mixing with the combustible gases arising from the fuel.

The above and other objects will be more readily apparent to those skilled within the art when taken in connection with the following detailed description and the structure shown in the drawings which consist of the novel features of construction, combination and arrangement of parts as will be hereinafter particularly pointed out in the appended claims.

In the drawings:—Figure 1 is a side elevation of the stove pipe embodying my invention. Fig. 2 is a vertical section through the same, and Fig. 3 is a horizontal section.

By reference now being had to the accompanying drawings wherein like and corresponding parts are designated by similar reference characters throughout the several views, the numeral 1 indicates a cylindrical casing having supported therein an air pre-heating chamber 2. Secured to the lower end of the casing 1 by a beaded connection 3 is an inverted conical section 4 having secured to its lower extremity by means of a beaded connection a cylindrical section 5. The plate 5 is connected to the upper end of the casing 1 by means of the beaded connec-

tions as shown and secured to the plate 5 is a cylindrical section 6, being of the same diameter as section 4. A damper 7 carried by shaft 8 journaled within the section 6 is adapted to be operated by a handle 9 in the usual manner. Leading to the upper end of the section 6 is an over-draft opening 10 having a door 11 hingedly secured thereto whereby the over-draft leading to the device may be suitably controlled.

The structure herein described is adapted to form one section of an ordinary stove pipe and the sections 4 and 6 thereof being adapted to be connected to the adjacent sections of the stove pipe are of the same diameter as the stove pipe to form a continuation thereof.

Whereas this device is shown as being a section of an ordinary stove pipe, it is, of course, to be understood that the same may be placed within a flue or chimney with the same satisfactory results.

The air pre-heating chamber 2 comprises a cylindrical tube 12 which is of less exterior diameter than the interior diameter of the outer casing thereby forming a passage way 13 there between. Secured to the lower end of the tube 12 by means of the beaded connection 14 is an inverted conical section 15, having a plurality of openings 16 formed therein for a purpose which will be later described. The upper end of the tube 12 is closed by means of the wall 17. For supporting the tube 12 within the casing 1 I have provided a plurality of tubes 18 which are in communication with the chamber 2 and the atmospheric air whereby a suitable air supply will be directed to the air pre-heating chamber 2. To retard the air as it enters the air pre-heating chamber 2 I provide adjacent the openings which are in communication with the tubes 18 baffle plates 19 which are suitably secured to the inner periphery of the tube 12 by any suitable means or by rivets 20 as shown.

In the operation of the device the cold air is permitted to enter the tubes 18 in the directions of the arrows as shown where it enters the chamber 2, the air passing down the chamber 2 will then become heated by hot gases arising from the combustion of the fuel and subsequently passing through the openings 16 in small streams where the

pre-heated air is delivered to the interior of the fuel consumer and combines with the combustible gases.

I claim:

- 6 1. In a fuel saving device comprising a casing, an air pre-heating chamber suspended therein, the outer diameter of the air pre-heating chamber being considerably less than the interior diameter of the casing 10 thereby forming a passage way around the chamber, a plurality of tubes forming inlet pipes for the air to said pre-heating chamber and adapted to support said chamber within the casing, an inverted conical 15 shaped bottom secured to said pre-heating chamber and provided with a plurality of outlet openings, an inwardly tapering section connected at one end to said casing and adapted to be connected at its opposite end 20 to the flue leading to the furnace, for the purpose set forth.
2. In a fuel saving device comprising a flue having two sections of the same diameter throughout, a casing of larger diameter 25 than the flue sections, a circular plate connecting one section of the flue with the casing, an inverted conical section connecting

the casing with the other section of the flue, an air pre-heating chamber suspended within the casing, the casing having a plurality 30 of openings formed therein, an arcuate tube leading from each opening and communicating with openings formed within one end of the air pre-heating chamber, the tubes providing means for rigidly suspending the air pre-heating chamber in spaced relation within the casing, upwardly and inwardly projecting baffle plates mounted upon the inner walls of the air pre-heating chamber in front of the openings formed 35 therein, an inverted conical shaped bottom secured to said pre-heating chamber and provided with a plurality of outlet openings and the inverted conical shaped bottom of the air pre-heating chamber resting within 40 and in spaced relation with the conical section of the casing for the purpose set forth.

In witness whereof, I hereunto subscribe my name to this specification in the presence of two witnesses.

WILLIAM C. BLASKE.
